US0D1059170S

(12) United States Design Patent (10) Patent No.: US D1,059,170 S
(45) Date of Patent: * Jan. 28, 2025

(54) HANGER BAR

(71) Applicant: Pratt Corrugated Holdings, Inc.,
Brookhaven, GA (US)

(72) Inventors: Shifeng Chen, Newport News, VA
(US); Greg Sollie, Sharpsburg, GA
(US); Hannah Conrad, Memphis, TN
(US); Randy Ball, Peachtree City, GA
(US)

(73) Assignee: Pratt Corrugated Holdings, Inc.,
Brookhaven, GA (US)

() Term: 15 Years

(21) Appl. No.: 29/848,658

(22) Filed: Aug. 4, 2022

Related U.S. Application Data

(63) Continuation of application No. 29/765,524, filed on
Jan. 8, 2021, now Pat. No. Des. 964,163.

(57) CLAIM

The ornamental design for a hanger bar, as shown and described.

DESCRIPTION

FIG. 1 is a perspective view of the hanger bar.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines in the drawings depict portions of the hanger bar that form no part of the claimed design.

1 Claim, 4 Drawing Sheets
